CARLO RUBINO, OF FLUSHING, NEW YORK

SELF-OPENING ENVELOPE

Application filed April 13, 1931. Serial No. 529,620.

This invention relates to new and useful improvements in a self-opening envelope.

The invention has for an object the production of a self-opening envelope which is characterized by a string extended along the bend of the flap of the envelope and having a projecting end capable of being pulled to cause the shearing open of the envelope along the flap bend.

It is a still further object of this invention to make use of a tab pasted within the envelope at one end and holding down the inner end of the string.

Furthermore, it is proposed to paste the string along its full length within the bend.

A still further object of this invention is the provision of means for opening either the longitudinal side of the envelope or one of the transverse sides.

It is proposed to arrange a string extended along the bend of the flap of the envelope, and the bend at one of the sides and to have both ends projecting to allow opening of the longitudinal sides or a transverse side.

Furthermore, as another object of this invention, it is proposed to arrange the string mentioned in the previous paragraph, in a manner so that when one end is drawn to open one side, the other end is drawn in so as not to be extended, making it impossible to open the other side.

As another object, it is proposed to provide a knife edge to act against the string and cut the string if one of the sides of the envelope is opened.

Another object of this invention is to construct a device of the class mentioned which is of simple, durable construction, desirable in use and efficient in action, and which can be manufactured and sold at a reasonable cost.

For further comprehension of the invention, and of the objects and advantages thereof, reference will be had to the following description and accompanying drawings, and to the appended claims in which the various novel features of the invention are more particularly set forth.

In the accompanying drawings, forming a material part of this disclosure:—

Fig. 1 is an elevational view of an envelope constructed according to this invention.

Fig. 2 is a sectional view taken on the line 2—2 of Fig. 1.

Fig. 3 is a view similar to Fig. 1 but illustrating a modified construction. 55

Fig. 4 is a sectional view taken on the line 4—4 of Fig. 3.

Fig. 5 is a longitudinal sectional view of the knife member used for cutting the string. 60

Fig. 6 is a similar view to Fig. 1, showing the opening string located in the bottom side of the envelope.

Figs. 7, 8 and 9 are similar views to Fig. 1, showing other forms of the invention. 65

The self-opening envelope, according to this invention, consists of an envelope 10 which may be of any design and construction. It may be of any size or any quality of paper. The envelope 10 is provided with a flap 11 which is normally open and which may be pasted down upon the back of the envelope to seal its contents. For this purpose, gum material 12 is arranged upon the edge. 70 A string 13 is pasted in the bend between the flap 11 and the remaining portion of the envelope. 75

One end 14 of the string is held stationary by a paper tab 15 which is pasted within the envelope. The end 14 is bent substantially 80 at right angles to the main portion of the string so that the tab 15 may be of sufficient length to firmly hold it in place. The other end 16 of the string is slightly extended from the side of the envelope so that it may be 85 drawn to cause opening of the envelope after the flap has been sealed.

In the modified form of the invention illustrated in Figs. 3 to 5 inclusive, a means 90 has been disclosed for opening the envelope either along the longitudinal side or a transverse end. This means comprises a small metallic tube 17 held within one corner of the envelope by a tab 18, preferably made from a sheet of cloth. This tab has a portion 95 pasted down within the inside of the envelope and another portion encircling the tubular member. A string 19 extends through the tubular member 17 and in one direction along 100

the bend of the flap 11, while in the other direction along the bend of one of the ends of the envelope. Tabs 20 serve to slidably support the string 19 so that it may be longitudinally drawn. It is requisite that the string be not pasted down so that it may move. Each of the ends 16 of the string project from the envelope so that either end may be drawn and pulled to cause opening of the envelope.

Knots 21 are formed in the string 19 at portions on opposite sides of the tube 17 so as to limit drawing of the string in one direction or in the other. The ends of the tube 17 are sharpened, as indicated by reference numerals 22, constituting knife edges for the purpose of cutting the string when it is drawn.

The operation may be understood by assuming the flap of the envelope shown in Fig. 3 closed. The projecting end of the string 19 from the flap may be drawn upwards so as to cut the flap at the bend and cause opening of the envelope. When the bend has been cut to the end where the tube 17 is located, further drawing of the string causes the string to move if it has not already done so during the cutting of the bend to a position in which one of the knots 21 engages against one of the ends of the tubular member 17. The knot is of such size so that it cannot pass through the tube, and consequently, further pulling of the string results in the knife edge on the other end of the tube cutting it.

After the string moved, the remaining extending end 16 was drawn in so that the end of the envelope cannot be opened. In the event that the person wishes to open the end instead of the longitudinal side, it would be necessary only to draw the other end of the string instead of the one which was drawn. The operation is very identical and will be readily understood without further amplification. The advantage of opening the longitudinal side or the transverse end of the envelope resides in the fact that quite often persons wish to save the envelope and are particular to have the envelope opened on one side or on one end according to their desires.

In Fig. 7 three tabs 20' are provided for holding string 13 in position, while in Fig. 8 only two are used to hold string 13. In Fig. 9 the string is glued or cemented to the envelope 10 without any tab. In Figs. 7, 8 and 9, both ends 16 of the string 13 extend out of the envelope 10.

While I have shown and described the preferred embodiment of my invention, it is to be understood that I do not limit myself to the precise construction herein disclosed and the right is reserved to all changes and modifications coming within the scope of the invention as defined in the appended claims.

Having thus described my invention, what

I claim as new, and desire to secure by United States Letters Patent is:

1. A self-opening envelope, comprising sheet material in the form of an envelope and having a flap capable of being closed, and means for opening one of the longitudinal sides or a transverse end, comprising a small tubular member attached within one of the corners of the envelope, a string extending through the tubular member and extending along the flap bend and one of the ends, both of the ends of the string projecting slightly from the envelope, and knots being formed in the string on opposite sides of the tubular member. 70 75 80

2. A self-opening envelope, comprising sheet material in the form of an envelope and having a flap capable of being closed, and means for opening one of the longitudinal sides or a transverse end, comprising a small tubular member attached within one of the corners of the envelope, a string extending through the tubular member and extending along the flap bend and one of the ends, both of the ends of the string projecting slightly from the envelope, and knots being formed in the string on opposite sides of the tubular member, the ends of the tubular member being sharpened to form knife edges to cut the string after one section or the other section on one or the other sides of the tubular member is fully drawn. 85 90 95

3. A self-opening envelope, comprising sheet material in the form of an envelope and having a flap capable of being closed, and means for opening one of the longitudinal sides or a transverse end, comprising a small tubular member attached within one of the corners of the envelope, a string extending through the tubular member and extending along the flap bend and one of the ends, both of the ends of the string projecting slightly from the envelope, and knots being formed in the string on opposite sides of the tubular member, said knots being larger than the tubular member so as to be unable to pass through the tubular member. 100 105 110 115

4. A self-opening envelope, comprising sheet material in the form of an envelope and having a flap capable of being closed, and means for opening one of the longitudinal sides or a transverse end, comprising a small tubular member attached within one of the corners of the envelope, a string extending through the tubular member and extending along the flap bend and one of the ends, both of the ends of the string projecting slightly from the envelope, knots being formed in the string on opposite sides of the tubular member, and means for severing the string from the envelope after the envelope is opened. 120 125

5. A self-opening envelope, comprising sheet material in the form of an envelope and having a flap capable of being closed, and means for opening one of the longitudi- 130

nal sides or a transverse end, comprising a small tubular member attached within one of the corners of the envelope, a string extending through the tubular member and extending along the flap bend and one of the ends, both of the ends of the string projecting slightly from the envelope, knots being formed in the string on opposite sides of the tubular member, and means for severing the string from the envelope after the envelope is opened, comprising knife edges formed on both sides of the tubular members.

In testimony whereof I have affixed my signature.
